CLAIM

The ornamental design for a payment terminal cover, as shown and described.

DESCRIPTION

FIG. 1 is a front perspective view of a payment terminal cover showing our new design;

FIG. 2 is a front view thereof;

FIG. 3 is a back view thereof;

FIG. 4 is a left side view thereof;

FIG. 5 is a right side view thereof;

FIG. 6 is a bottom view thereof;

FIG. 7 is a top view thereof; and,

FIG. 8 is another perspective view thereof.

1 Claim, 6 Drawing Sheets
